(57) CLAIM

The ornamental design for a rear element of a shoe upper, as shown and described.

DESCRIPTION

FIG. 1 is a perspective view of an rear element of a shoe upper showing the new design;

FIG. 2 is a side elevational view thereof; and,
FIG. 3 is a rear elevational view thereof.

The uneven broken lines in all figures showing the remainder of the shoe are for illustrative purposes only and form no part of the claimed design.
